STOP MECHANISM FOR KNITTING MACHINES

Stanley A. Wytovich, Allentown, Pa., assignor to
Blossom Products Corporation, Allentown, Pa.,
a corporation of Pennsylvania

Application July 10, 1946, Serial No. 632,572

12 Claims. (Cl. 66—167)

1

This invention relates to knitting machines, and, more particularly, to a device for stopping the machine when a predetermined quantity of fabric has been produced.

It is essential that the take-up reel upon which the knitted fabric is wound as it is being produced contain a constant quantity of the fabric and that there be no variation in the yardage of successive reels taken from the same machine or from a group of machines. This is necessary because the yardage is an important factor in the subsequent dyeing and finishing operations; the goods are marketed and sold on the basis of length; freight and other charges are based on yardage, etc.

Stop mechanisms heretofore incorporated in circular knitting machines, both of the rotating and stationary cylinder type, have not been wholly satisfactory for a number of reasons. Besides being complicated, or rather as a result of this, they have not been dependable in operation, because of frequent failure to function and stop the machine. Such stop mechanisms have not been sufficiently accurate in holding the fabric content of successive take-up reels to a constant quantity, the variation between reels being so great as to defeat the purpose for which the stop mechanism was intended.

The principal object of this invention is to provide a new and improved stop mechanism for circular knitting machines which will be dependable in operation and not subject to failure to stop the machine at the end of each production cycle; and which will be highly accurate so that successive take-up rolls will contain a constant quantity of knitting fabric.

A further object of the invention is a stop mechanism of the character described which comprises a relatively few number of parts, of simple construction, and not costly to manufacture. A further object is a stop mechanism for the purposes described which will be positive in operation. A still further object is a stop mechanism which can be readily applied to known types of circular knitting machines.

For the attainment of the foregoing and such other objects of invention as may appear or be pointed out herein I have shown an embodiment of my invention in the accompanying drawing, wherein:

Figure 1 is a front, elevational view of the lower, take-up portion of a circular knitting machine, incorporating the improved stop mechanism for a rotating cylinder construction;

Figure 2 shows the pair of contact rollers and

2

the lower portion of the rod to which they are secured;

Figure 3 is a sectional view taken on the line 3—3 of Figure 2;

Figure 4 is an elevational view, on enlarged scale, of the stop mechanism, showing a portion of the machine of Figure 1;

Figure 5 is a view similar to Figure 4 but showing certain of the parts in section;

Figure 6 is a top view of the improved device, showing a portion of the machine to which it is secured;

Figure 7 is an elevational view of the parts shown in Figure 6, taken from the front face thereof;

Figure 8 is a section taken on line 8—8 of Figure 6;

Figure 9 is an elevational view similar to Figure 7 but taken from the rear face of the device shown in Figure 6;

Figure 10 is an elevational view similar to Figure 9, but showing only certain of the parts thereof, in altered position; and

Figure 11 is a section taken on line 11—11 of Figure 6.

Referring to Figure 1, the circular knitting machine illustrated is the rotating cylinder type, although the invention can be applied to a stationary cylinder type by any one skilled in the art. The machine has a main supporting base 10 which is an annular ring of inverted-L section. To the depending flange portion of base ring 10 is secured at spaced points about its periphery, a number of supporting legs 9. To the upper face of base ring 10 is secured at spaced points about its periphery, the lower ends of a number of supporting braces 8, to the upper ends of which is secured an upper annular ring 7, which, together with upright bars 6, furnishes the support for the mechanism constituting the upper portion (not shown) of the knitting machine.

During the operative rotation of a circular knitting machine, a tube of fabric is formed in well-known manner, and is directed downwardly to a take-up mechanism. In the particular structure illustrated, as cylinder 24 is rotated (by means not shown) the fabric, knitted in tubular form at the upper portion of the machine, moves downwardly from rotating cylinder 24 to pass through a pair of long rollers 27. The fabric as it leaves rotating cylinder 24 is circular but becomes flattened when passing through rollers 27; hence, the tapering appearance of the tubular fabric as indicated at 5. The flattened fabric 4

leaving the rollers 27 is wound on take-up reel 30, as will be described.

The upper face of base ring 10 is annularly recessed to present a peripheral ledge 12 which supports, and serves as a bearing for a ring 20 which is annularly recessed to provide a peripheral shoulder 22 seated on ledge 12. Ring 20 is rotated from rotating cylinder 24 by means of a number of rods 23 which are secured to ring 20 and cylinder 24 at spaced points about their periphery.

Secured to, and depending from, ring 20 are a pair of brackets 25, the lower ends of which are provided with bearings 26 for the shaft 31 of the take-up reel. Rollers 27 have bearing supports (not shown) secured to ring 20. It is thus seen that main ring 20 and cylinder 24 rotate as a unit, and mounted on ring 20 to rotate therewith are the take-up reel 30, flattening rollers 27 and the tubular fabric 5, 4 coming off rotating cylinder 24.

Take-up shaft 31 is rotated, to wind the fabric thereon, by the following means: To shaft 31 is secured a worm wheel 32 meshing with worm 33 secured at the lower end of a short vertical shaft 34. Shaft 34 has a clutch 35-36 (the purpose of which will be presently explained) and is driven from a horizontal shaft 38 through gearing (not shown). Horizontal shaft 38 is journaled at its left end, Figure 1, in a bearing 21 depending from main ring 20 and by other bearings (not shown) and likewise secured to ring 20. At the left end of horizontal shaft 38 is secured a bevel pinion 39 which meshes with the bevel teeth of an annular rack 19 secured in underlying relation to the stationary base ring 10. Horizontal shaft 38 and vertical shaft 34 and their associated parts being carried, together with take-up shaft 31, brackets 25, etc., by main ring 20, the turning of ring 20 will cause rotation to be imparted to horizontal shaft 38 as bevel pinion 39 rides on stationary rack 19. In this manner, take-up rotation is imparted to take-up shaft 31 of the reel. The clutch 35-36 is provided in vertical shaft 34 for the purpose of compensating for the increasing diameter of the take-up reel as the fabric builds up. The clutch comprises a driven member 35 which is secured to rotate with the lower half of shaft 34, Figure 1, and a driving member 36 which is feathered on the upper half of shaft 34 so as to rotate therewith and yet be axially movable thereon. Clutch member 36 is moved axially (by means not shown) towards and away from clutch member 35 to provide an intermittent drive to the take-up reel. That is, take-up shaft 31 is not constantly driven but only for a portion of the time; this portion depends upon the diameter of the reel at the particular time and is controlled by the intermittent means associated with clutch member 36.

On one of the supporting braces 8 is mounted an electrical switch 13 which is shut-off to stop the machine when the take-up reel has built up to the predetermined fabric content. Lever 14 of switch 13 is connected by a rod or wire 15 to one leg 16 of a bell-crank lever 16-17 pivotally mounted to supporting brace 8 at 18. Means are provided on ring 20 to trip the switch by turning bell-crank lever 16-17 in a counterclockwise direction (as viewed in Figures 1 and 4) when the take-up reel has built up to the predetermined fabric content. The tripping means is secured to ring 20 by an L-shaped bracket 40-41, the horizontal flange 40 of which is screwed or

otherwise fastened to ring 20. As best seen in Figure 6, bracket 40-41 is not secured radially of ring 20, but at an angle such that, as the tripping mechanism (turning counterclockwise with ring 20) approaches bell-crank 16-17, a longitudinal axis through the tripping mechanism (i. e., parallel to bracket 40-41) will be substantially normal to a plane through bell-crank 16-17. The vertical flange 41 of the bracket has secured to its outer face a channel 42, in the recess of which is slidably retained a slide bar 50, as best seen in Figures 4, 5.

Slide bar 50 has an extent of longitudinal sliding movement relative to the bracket, limited by a pin 53 which projects outwardly from slide bar 50 and clears through an elongated slot 43 provided in the web of channel 42, the length of the slot determining the said limited sliding movement of bar 50. Pin 53 also serves to anchor one end of a tensile spring 37, the other end of which is secured to a pin 44 projecting outwardly of the channel 42. A second pin 51 is secured near the right end (Figures 6, 9) of slide bar 50, i. e., near the end adjacent bell-crank 16-17. To pin 51 is secured a contact finger 57. As best seen in Figure 9, the right end of the web of channel 42 is recessed by a notch 45 to receive pin 51 when slide bar 50 is in its leftmost position (as in Figure 9) with pin 53 abutting the left end of slot 43. In the leftmost position of slide bar 50 (shown in solid lines in Figures, 6, 9 and 7), its contact finger 57 will not strike vertical leg 17 of bell-crank 16-17 as the tripping mechanism passes the bell-crank as it turns counterclockwise (as viewed in Figure 6).

Slide bar 50 is latched in its leftmost, inactive position, against the rightward urgency of tensioned spring 37 to project contact finger 57 to active position, by a hook 52 at the left end of the slide bar which is held by a latch dog 62. Latch dog 62 is secured, as by the set-screw shown, to a lever 60 which is pivotally mounted at 61 to the vertical flange 41 of bracket 40-41. The angle of turning of lever 60 is limited by two closely spaced pins 63, see Figure 7. Near its distal end lever 60 carries a rod 64 disposed transversely of lever 60 and provided at its lower end, Figures 4 and 7, with a pair of contact rollers 71, 71. Rod 64 is mounted on lever 60 in a manner to provide for the following three adjustments: first, contact rod 64 may be adjusted longitudinally of lever 60, i. e., to left and right, as viewed in Figures 6, 7; second, contact rods 64 may be angularly adjusted in a plane normal to lever 60; third, contact rod 64 may be axially adjusted to raise or lower its contact rollers 71, Figure 7. These three adjustments are made possible by the mounting bracket, see Figure 11, comprised by two hubs 67, 77 integrally united with their bores, respectively, 68, 78 normal to one another. Bracket 61-77 is mounted on lever 60 which is slidably received in bore 78 of hub 77; and may be secured at any point along lever 60, and with contact rod 64 disposed in the desired angular relation, by means of set screw 79. Contact rod 64 is slidably received in bore 68 of hub 67 and is secured by set screw 69 so as to dispose its contact rollers 71, 71 at the proper distance from lever 60; a fourth adjustment is here provided, namely, the angular turning of contact rod 64 to orient its rollers 71, 71 as required.

Contact rollers 71, 71 are engaged by the periphery of the fabric being wound on take-up reel 30 when the fabric has built up to the predetermined amount, at which time contact roll-

ers 71, 71 are effective to stop the machine, as will be subsequently described. To improve the engagement of the fabric with the contact rollers and to compensate of any unevenness in the periphery of the fabric as it is wound on the take-up reel, contact rollers 71, 71 are pivotally mounted at the lower end of contact rod 64 so as to have a limited extent of turning movement. For this purpose, the lower end of contact rod 64 is bifurcated, as best seen in Figure 3, to provide two forks 65 between which is pivotally mounted a spindle 70 which is centrally flattened to be received within the forks 65, 65; spindle 70 is held in place by pivot screw 66 passed through apertures in forks 65, 65 and an aperture centrally located in spindle 70. Spindle 70, except for its central flattened portion, is in the form of a round rod, upon which are rotatively mounted the pair of contact rollers 71, 71. The ends of spindle 70 are threaded for nuts 72 which retain the contact rollers in place, Figure 2.

Contact rod 64 is adjusted, in the manner described above, to present its pair of contact rollers 71, 71 in proper position relative to take-up reel 30 so that when the reel has built-up to the predetermined fabric content, the periphery or top layer of the fabric will engage the contact rollers to move the rollers and contact rod 64 upwardly, as viewed in Figure 7. This upward movement of the contact rod is communicated to lever 60 which likewise turns upwardly, Figure 7, for a limited extent. At the start of a new cycle of operation, i. e., when the machine is started with its take-up reel empty, slide bar 58 is moved leftwardly, as viewed in Figures 9, 6 and 7, where it is latched, by engagement of its hook 52 with latch dog 62, in inoperative position with its trip finger 57 disposed leftwardly of bell-crank 16-17. This latched, inoperative position is shown in Figures 9, 6 and 7 in solid lines; as perhaps best seen in Figure 6, in this position of slide bar 58, its contact or trip finger 57 will be ineffective to engage the vertical leg 17 of bell-crank 16-17, as the stop mechanism, carried by ring 20, turns counterclockwise, as viewed in Figure 6, therewith. When, however, the take-up reel is built up to the predetermined fabric content and contact rollers 71, 71 are engaged, as described above, and the lever 60 is turned on its pivot 61, upwardly in Figure 7, latch dog 62, secured on lever 60 as already described, is withdrawn from engagement with hook 52, whereupon the tensioned spring 37 moves slide bar 58 rightwardly (indicated by dot-and-dash position in Figures 6, 7 and 9). In this rightward position of slide bar 58, its finger 57 is placed so that it will engage vertical leg 17 of bell-crank 16-17; hence the next time the stop mechanism, following the release of its slide bar 58, passes bell-crank 16-17, finger 57 will engage vertical leg 17, and turn the bell-crank counterclockwise, as viewed in Figure 4, thus pulling wire 15, Figure 1, downwardly to operate electrical switch 13 and stop the machine.

In the accompanying drawings, the invention has been shown merely by way of example and in preferred form; but obviously many variations and modifications may be made therein which will still be comprised within its spirit. It is to be understood, therefore, that the invention is not limited to any specific form or embodiment, except insofar as such limitations are specified in the appended claims.

I claim:

1. A stop mechanism for a circular knitting machine of the type having an annular ring supported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, a bell-crank lever pivotally mounted on the machine frame with its horizontal leg articulated to said switch and with its vertical leg disposed close to the said rotating ring, an angle bracket secured to the said ring to dispose its vertical flange, when approaching the said bell-crank lever, normal to a plane therethrough, a channel secured to one face of the said bracket flange and having an elongated slot in its web and a pin projecting therefrom, a bar slidably mounted in the recess of said channel and provided with a pin clearing through said slot, a trip finger at its end adjacent the said bell-crank lever, and a hook at its other end, a tensile spring secured between the said pins of the slide bar and channel, a lever pivotally mounted at one end to the other face of said bracket flange for a limited extent of vertical turning and provided with a latch dog adapted in the lower position of the lever to engage the said hook to retain the slide bar in inoperative position with its trip finger spaced from the said bell-crank lever and with the said spring tensioned to move the bar to operative position, a contact rod secured transversely of said lever, and a pair of contact rollers mounted at the lower end of said rod and adapted to be engaged by the peripheral fabric of the take-up reel when built-up to its said predetermined fabric content.

2. A stop mechanism for a circular knitting machine of the type having an annular ring supported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, means on the machine frame for operating the said switch, an angle bracket secured to the said ring to dispose its vertical flange, when approaching the said switch operating means, normal to a plane therethrough, a channel secured to one face of the said bracket flange and having an elongated slot in its web and a pin projecting therefrom, a bar slidably mounted in the recess of said channel and provided with a pin clearing through said slot, a trip finger at its end adjacent the said switch operating means, and a hook at its other end, a tensile spring secured between the said pins of the slide bar and channel, a lever pivotally mounted at one end to the other face of said bracket flange for a limited extent of vertical turning and provided with a latch dog adapted in the lower position of the lever to engage the said hook to retain the slide bar in inoperative position with its trip finger spaced from the said switch operating means and with the said spring tensioned to move the bar to operative position, a contact rod secured transversely of said lever, and a contact roller mounted at the lower end of said rod and adapted to be engaged by the peripheral fabric of the take-up reel when built-up to its said predetermined fabric content.

3. A stop mechanism for a circular knitting machine of the type having an annular ring sup-

ported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, a bell-crank lever pivotally mounted on the machine frame with its horizontal leg articulated to said switch and with its vertical leg disposed close to the said rotating ring, an angle bracket secured to the said ring to dispose its vertical flange, when approaching the said bell-crank lever, normal to a plane therethrough, a bar slidably mounted on one face of the said bracket flange and provided with a trip finger at its end adjacent the said bell-crank lever, and a hook at its other end, a tensile spring tensioned to move the said slide bar towards the bell-crank, a lever pivotally mounted at one end to the other face of said bracket flange for a limited extent of vertical turning and provided with a latch dog adapted in the lower position of the lever to engage the said hook to retain the slide bar in inoperative position with its trip finger spaced from the said bell-crank lever and with the said spring tensioned to move the bar to operative position, a contact rod secured transversely of said lever, the lower end of said rod being adapted to be engaged by the peripheral fabric of the take-up reel when built-up to its said predetermined fabric content.

4. A stop mechanism for a circular knitting machine of the type having an annular ring supported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, means mounted on the machine frame for operating the said switch, an angle bracket secured to the said ring to dispose its vertical flange, when approaching the said switch operating means, normal to a plane therethrough, a bar slidably mounted on one face of the said bracket flange and provided with a trip finger at its end adjacent the said switch operating means, and a hook at its other end, a tensile spring stretched between the said slide bar and bracket flange, a lever pivotally mounted at one end to the other face of said bracket flange for a limited extent of vertical turning and provided with a latch dog adapted in the lower position of the lever to engage the said hook to retain the slide bar in inoperative position with its trip finger spaced from the said switch operating means and with the said spring tensioned to move the bar to operative position, a contact rod secured transversely of said lever, and a pair of contact rollers mounted at the lower end of said rod and adapted to be engaged by the peripheral fabric of the take-up reel when built-up to its said predetermined fabric content.

5. A stop mechanism for a circular knitting machine of the type having an annular ring supported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, means mounted on the machine frame for operating the said switch, a slide bar, means for mounting the said bar on the said rotating

ring for movement towards and from the said switch operating means, the end of the slide bar adjacent the said switch operating means being provided with a finger and its other end with a hook, spring means urging the slide bar towards the said switch operating means, a lever pivotally mounted on the said rotating ring and provided with a latch dog adapted to engage the said hook to retain the slide bar in inoperative position with its finger spaced from the said switch operating means and with the said spring tensioned to move the bar to operative position, and a contact rod on the said lever, the lower end of said rod being adapted to be engaged by the peripheral fabric of the take-up reel when built-up to its said predetermined fabric content.

6. The combination according to claim 5 further provided with means for mounting the said contact rod on the said lever for longitudinal movement along the lever and for angular adjustment in a plane normal to the lever, said mounting means further providing axial movement of the said contact rod to adjust its said lower end relative to the lever.

7. The combination according to claim 5 further provided with a pair of contact rollers mounted at the said lower end of the rod and with means for mounting the said contact rod on the said lever, said contact rod being rotatively adjusted to orient its said pair of contact rollers at desired angular relation to the said lever.

8. The combination according to claim 5 further provided with a pair of contact rollers pivotally mounted at the lower end of the contact rod.

9. The combination according to claim 5 further provided with means for adjustably mounting the said contact rod on the lever, said mounting means comprising a pair of hubs integrally united with their axes normal to one another, the said contact rod and lever being received in the bore of the respective hubs, said hubs being provided with set screws for securing the respective contact rod and lever in axial and rotational adjusted positions.

10. The combination according to claim 5 wherein the said lower end of the contact rod is bifurcated to provide a pair of forks, a short rod flattened at its central portion and pivoted thereto at between the said pair of forks, and a pair of rollers rotatively mounted at the ends of the said short rod.

11. A stop mechanism for a circular knitting machine of the type having an annular ring supported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, means mounted on the machine frame for operating the said switch, a bar slidably mounted on the said rotating ring for outward and inward movement relative thereto and effective in outward position to actuate the said switch operating means, spring means urging the said slide bar to outward, operative position, latch means normally holding the slide bar in inward, inoperative position, and means for releasing the slide bar, said means including a contact element adapted to be engaged by the peripheral fabric of the take-up reel when built-up to its said predetermined fabric content.

12. A stop mechanism for a circular knitting

machine of the type having an annular ring supported on the machine frame and rotated during the knitting operation, a take-up reel carried by the said ring, and an electrical control switch secured on the machine frame, said stop mechanism being adapted to stop the machine when the said take-up reel has built-up to a predetermined fabric content, comprising, in combination, means mounted on the machine frame for operating the said switch, a bar slidably mounted on the said rotating ring for outward and inward movement relative thereto and effective in outward position to actuate the said switch operating means, said slidable bar being normally held in inward, inoperative position, and means for causing movement of the slidable bar

to outward, operative positions, said means including a contact element adjustably positioned relative to the center of said take-up reel for engagement by the peripheral fabric when the reel is built-up to its said predetermined fabric content.
